Primary Examiner — Ricky Pham*(74) Attorney, Agent, or Firm* — Yong Chen(57) CLAIM

The ornamental design for an egg cooker, as shown and described.

DESCRIPTION

FIG. 1 is a front view of an egg cooker of the present invention.

FIG. 2 is a back view thereof.

FIG. 3 is a left view thereof.

FIG. 4 is a right view thereof.

FIG. 5 is a top view thereof.

FIG. 6 is a bottom view thereof; and,

FIG. 7 is a perspective view thereof.

The broken line showing of certain portions of the egg cooker is included for the purpose of illustration only and forms no part of the claimed design.
